WILLIAM FRANK SEAVERY, OF PORTLAND, MAINE.

Letters Patent No. 88,814, dated April 13, 1869.

IMPROVEMENT IN BLIND-CATCH.

The Schedule referred to in these Letters Patent and making part of the same.

To all whom it may concern:

Be it known that I, WILLIAM FRANK SEAVERY, of Portland, in the county of Cumberland, and State of Maine, have invented a new and useful Improved Blind-Catch; and I hereby declare the following to be a full, clear, and exact description thereof, which will enable others to make and use my invention; reference being had to the accompanying drawings, forming part of this specification, in which—

Figure 1 shows a bottom plan of my invention, with the covering-plate removed.

Figure 2, a view of the same, when attached to the bottom of a blind.

The catches now in use for blinds are all open to criticism from the fact that when the blind is to be closed, it is necessary to raise the window some distance, and extend the arm and hand, in order to reach the catch, before it can be released from its attachment to the house.

In stormy weather, whether in summer or winter, this necessarily exposes the person, and not unfrequently in driving storms the rain or snow beats into the room.

To obviate this difficulty, by means at once simple, cheap, and effective, is the purpose of my invention.

My device is the application of a lever to a blind-catch, said lever having an arm long enough to extend to the inner edge of the blind, by means of which the catch may be detached from its fastenings without extending the arm or raising the window more than a few inches.

This arm also gives a leverage, which assists in closing the blind.

The operation of my invention will be readily understood by reference to the drawings.

a shows the lever attached to the catch *b*, which has the spurs *c* and *d*, the former catching when the blind is open and the latter when it is shut. (See fig. 2.)

The spring shown at *e* is a spiral.

The catches and spring are here enclosed in a box, *f*, to which a cover is secured by a screw passing through *g*, which also serves as a pivot for the lever.

An opening in the box at *i* *j* allows the lever to swing a proper distance, and the edge *j* serves as a bearing-shoulder, or fulcrum, for the arm when employed to draw the blind to, after it has been released from the wall of the house.

The length of the lever-arm is shown in fig. 2, as are also at *h*, the stubs or staples on the window-sill and house.

The end of the lever-arm is formed into a ring for the finger.

When the blind is to be closed, the window is raised to a sufficient height to allow the hand to be put out.

Catching the ring with the fore-finger, the lever may be drawn out a short distance beyond the blind, disengaging the catch.

It will be observed as a point of convenience that the same motion which frees the blind draws it toward the window, requiring the exertion of but very little strength.

From the slight distance to which it is necessary to raise the window, no water or snow can enter, and only the hand need be exposed.

The catches *c* and *d*, shown in the drawing, enclose the staple on three sides, thus preventing the usual objectionable rattle in windy weather.

I do not claim the spring-catch, nor the method of its attachment to the blind; neither do I claim operating the spring-catch by a lever.

J. Currier's patent, No. 72,609, December 24, 1867, is different from mine in construction, and is not intended to effect the same purpose, and I do not claim the subject of his invention.

The particular object of my invention is to produce a blind-catch by which the blind, when open, can be unhooked and swung to by an elongated lever, the inner end of which is so near to the window that a person is not compelled to stretch the body out of the window in order to reach the catch, but simply to extend the hand far enough to reach the bottom edge of the blind next to the window, to which point the elongated lever extends.

My device is attached to the bottom edge of the blind, and the lever *a* swings or is operated in a horizontal plane; but

What I do claim as my invention, and desire to secure by Letters Patent, is—

A blind-catch, constructed and arranged as herein set forth and described.

WM. FRANK SEAVERY.
